UNITED STATES PATENT OFFICE.

EDWARD J. ELSAS, OF BLUE MOUND, MISSOURI.

BIT-HOLDER.

1,001,376.

Specification of Letters Patent. Patented Aug. 22, 1911.

Application filed June 23, 1909. Serial No. 503,906.

To all whom it may concern:

Be it known that I, EDWARD J. ELSAS, a citizen of the United States, residing at Blue Mound, in the county of Livingston 5 and State of Missouri, have invented a new and useful Bit-Holder, of which the following is a specification.

This invention has relation to bit holders and consists in the novel construction here- 10 inafter described shown and claimed.

More particularly the invention relates to means for securely holding the shank of a bit in proper engagement with a socketed holder during the twisting strain while the 15 bit is being used for boring purposes and to provide such means in which friction caused by engaging and disengaging the members is reduced to a minimum and in which the possibility of the parts becoming 20 stuck or wedged together to such an extent as to require hammering or knocking to disengage them is eliminated. Furthermore the parts when connected to each other are firmly held and braced against the twisting 25 strain and do not require the use of securing screws or nuts as are usually employed in similar devices at the present time.

In the accompanying drawings:—Figure 1 is a side elevation of the upper portion of 30 the bit. Fig. 2 is a sectional view of part of the holder. Fig. 3 is an enlarged perspective view of part of the bit. Fig. 4 is a transverse sectional view of the bit and holder engaged. Fig. 5 is a transverse sectional view of the bit on the line 5—5 of 35 Fig. 3. Fig. 6 is a transverse sectional view of the bit on the line 6—6 of Fig. 3.

The device comprises a holder 1 having a concentrically positioned socket 2 which is 40 open at one end. The holder 1 is also provided at its end and at the side of the socket 2 with a recess 3 one wall 4 of which is radially disposed with relation to the axis of the holder 1 and the wall 5 of which 45 is spirally disposed with relation to the axis of the holder 1. The holder 1 carries a stop 6 which projects into the socket 2 of the said holder and the said stop is provided with a beveled end 7. A bit 8 is pro- 50 vided upon its shank with a longitudinally disposed peripheral groove 9 which terminates at its lower or inner end in a laterally disposed branch 10 having its bottom wall 11 constituting a cam. The socket 2 of the 55 holder 1 is adapted to snugly receive the shank of the bit 8 and the stop 6 is adapted

to pass along the groove 9 in the shank of the bit 8 and the beveled end 7 thereof is adapted to wedge upon the cam wall 11 of the groove branch 10 when the bit is turned 60 upon its axis with relation to the holder 1.

The bit 8 is provided adjacent its shank with a shoulder 12 and the said shoulder is provided with a lug 13 which is adapted to enter and fit snugly within the recess 3 at 65 the end of the holder 1 when the bit is turned upon its axis with relation to the holder and the beveled end of the stop 6 is wedged against the cam wall 11 of the groove branch 10. The groove branch 10 in 70 the shank of the bit 8 is enough longer in a direction longitudinally of the bit, than the thickness of the stop 6 in the same direction to permit the engagement and disengagement of the lug 13 and the recess 3. Therefore 75 it will be seen that when the shank of the bit 8 is inserted in the socket 2 provided in the holder 1 and the parts are engaged in position as hereinbefore indicated 80 that the twisting strain to which the bit 8 is subjected, while it is used for boring purposes is in a great measure resisted by the lug 13 in engagement with the radially disposed wall 4 of the recess 3. At the same 85 time the end of the holder 1 is in close contact with the shoulder 12 and thus the thrust strain to which the bit 8 is subjected is borne by the end of the holder 1. Therefore the stop 6 is not subjected to any great extent 90 to either strain and the frictional contact between the said stop and bottom of the groove branch 10 is merely enough to prevent the bit from having a tendency to turn in the holder 1 when the bit 8 is turned in a direction opposite to that in which the bit is 95 turned when it is performing the boring operation. Therefore it will be seen that undue friction between the stop 6 and the groove branch 10 is eliminated and hence 100 these parts are not subjected to unnecessary wear and when it is desired to disconnect the bit 8 from the holder 1 it is necessary only to pull the said bit in a direction away from the end of the holder when the lug 13 105 will be moved away from the recess 3 and then the said bit is free to rotate in the holder 1 until the stop 6 is brought into alignment with the lower or inner end of the groove 9 when the said stop may be moved 110 along the said groove and the bit 8 is separated from the holder 1. Therefore it will be seen that in order to effect the separation

of the parts it is not necessary to use force or to apply a wrench or other tool to the parts. Furthermore when the parts are connected together in the manner as indicated they are securely retained in their proper relation by reason of the twist strain to which the bit is subjected during the boring operation and consequently the necessity of securing screws or nuts is overcome.

10 Having described the invention what I claim as new and desire to secure by Letters Patent is:—

The combination of a socketed holder having at one end and at the side of the socket 15 a recess with one wall radially disposed with relation to the axis of the holder and another wall spirally disposed with relation to the axis of the holder, a fixed stop carried by the holder and projecting from the side 20 thereof into the socket and having a beveled end, a bit having its shank provided with a peripheral groove longitudinally disposed and terminating at its inner end in a laterally disposed branch with its bottom wall 25 forming a cam, the socket of said holder

adapted to snugly receive the shank of the bit and the stop adapted to pass along said groove and the beveled end thereof adapted to wedge upon the cam, when the bit is turned upon its axis with relation to the holder, said bit having adjacent its shank a shoulder provided with a lug adapted to enter and snugly fit within the recess at the end of the holder when the bit is turned upon its axis with relation to the holder and the beveled end of the stop is wedged against the cam, the groove in the bit shank being enough larger in a direction longitudinally of the bit than the thickness of the stop in the same direction to permit the engagement and disengagement of the lug and recess.

In testimony that I claim the foregoing as my own, I have hereto affixed my signature in the presence of two witnesses.

EDWARD J. ELSAS.
